UNITED STATES PATENT OFFICE,

MORRIS H. RUPERT, OF MOUNT PLEASANT, PENNSYLVANIA.

WINDOW-SCREEN.

No. 920,659

Specification of Letters Patent.

Patented May 4, 1909.

Application filed June 15, 1908. Serial No. 438,539.

To all whom it may concern:

Be it known that I, MORRIS H. RUPERT, a citizen of the United States of America, residing at Mount Pleasant, in the county of 5 Westmoreland and State of Pennsylvania, have invented certain new and useful Improvements in Window-Screens, of which the following is a specification, reference being had therein to the accompanying drawing.

10 This invention relates to window screens, and the objects of my invention are, first, to provide a window with a novel screen that can be operated in conjunction with a window sash; second, to obviate the necessity of 15 using detachable screen frames; third, to provide a window frame with a concealed screen that cannot be observed when a screen is not being used; and fourth, to provide a simple, durable and inexpensive structure, 20 easily manipulated, effective for excluding flies and similar insects from a compartment and presenting a neat appearance. I attain the above objects by a structure that will be presently described and then specifically 25 pointed out in the appended claim.

In the drawings, figure 1 is a front elevation of a portion of a window frame equipped with my screen, Fig. 2 is a vertical sectional view of the same, Fig. 3 is an enlarged vertical sectional view of a portion of a window frame illustrating a simplified form of screen, and Fig. 4 is a longitudinal sectional view of a portion of the same.

In the accompanying drawings, I have 35 illustrated a window frame comprising stiles 1, a sill 2, a sill-plate 3, a lintel 4, guide strips 5, 5^a an upper sash 6 and a lower sash 7.

The sill 2 is provided with a longitudinal recess 8 for a revoluble roller 9 upon which is 40 wound a flexible wire screen 10, said screen being secured to a cleat 11 fixed to the inner side of the lower rail 12 of the sash 7. The cleat 11 is guided by the strips 5^a. These strips are of less length than the sides of the 45 frame and not only constitute a guide for the cleat, but also form a means for retaining the sill plate in position as the inner end of the sill plate is positioned below and directly beneath the lower ends of the strips 5^a.

50 The revoluble roller 9 is provided with a pulley 13, and passing over said pulley is a

cable 14. This cable is attached to the cleat 11 and passes over another pulley 15 at the upper end of a window frame, said cable being secured to the sash 7, as at 16. 55

The sill plate 3 is detachable, whereby easy access can be had to the recess 8 and said sill plate is cut away to provide a clearance for the screen 10 and the cable 14.

It is apparent that when the sash 7 is 60 raised the screen 10 will follow said sash, and as said screen is of a width corresponding to said sash the opening provided by the raised sash 7 will be closed by the wire screen. 65

The object of the cable 14 is to rotate the roller 9 and wind the screen 10 thereon when the sash 7 is lowered.

In Figs. 3 and 4, I have illustrated a simplified form of my invention, wherein the 70 cable 14 and the pulleys 13 and 15 are dispensed with. I use a spring roller 17 similar to a curtain shade roller, this roller 17 remaining under tension when the sash is open, consequently, winding the screen 10 upon 75 the roller when the sash is closed. The roller 17, similar to the roller 9 is journaled in suitable bearings 18 provided therefor in the recess 8.

During the winter, when the screen 10 is 80 not being used, the cleat 11 can be detached from the sash, the sill plate 3 removed and the cleat placed in the recess 8. With the sill plate 3 replaced, the window will present an ordinary appearance, and the screen 10 85 will be protected for future use.

It is thought that the operation and utility of my invention will be fully understood, and I reserve the right to make structural changes in the elements of my invention without departing from the spirit and scope of the same. 90

Having now described my invention, what I claim as new, is:—

The combination with a window-frame having a recessed sill and a sash, of bearing 95 brackets positioned against the end walls of said recess, means for securing said brackets in position a roller arranged in the recess and having its ends journaled in said brackets, a detachable sill plate for closing said recess, a 100 screen wound upon said roller, a cleat attached to one end of said screen and adapted to be

detachably connected to the front of the lower rail of said sash, a pulley carried at one end of said roller, a pulley revolvably supported from one of the sides of said frame near the top thereof, a cable attached to said cleat and passing over said pulleys and connected with the upper rail of said sash, and guide strips for the cleat secured to the window-frame

10
said strips further constituting means for retaining the sill plate in position.

In testimony whereof I affix my signature in the presence of two witnesses.

MORRIS H. RUPERT.
